(57) **CLAIM**

The ornamental design for a handbag handle, as shown and described.

DESCRIPTION

FIG. 1 is a side-front elevational view of a handbag handle showing my new design therefor, with the handbag shown in broken lines as environment only and forming no part of the design;

FIG. 2 is a side view of the handbag handle of FIG. 1; FIG. 3 is a side view opposite FIG. 2 of the handbag handle of FIG. 1;

FIG. 4 is a front view of the handbag handle of FIG. 1;

FIG. 5 is a rear view of the handbag handle of FIG. 1;

FIG. 6 is a top view of the handbag handle of FIG. 1; and,

FIG. 7 is a bottom view of the handbag handle of FIG. 1.

1 Claim, 7 Drawing Sheets
